UNITED STATES PATENT OFFICE.

J. N. DUDLEY, OF MITCHELL, IOWA.

IMPROVEMENT IN PORTABLE CALENDARS.

Specification forming part of Letters Patent No. 35,143, dated May 6, 1862.

To all whom it may concern:

Be it known that I, J. N. DUDLEY, of Mitchell, in the county of Mitchell and State of Iowa, have invented a new and Improved Calendar; and I do hereby declare that the following is a full, clear, and exact description thereof, reference being had to the accompanying drawings, making a part of this specification, in which—

Figure 1 shows the improved calendar complete. Fig. 2 is a longitudinal section through Fig. 1. Fig. 3 is an end view of the calendar-stem. Fig. 4 is a view showing the arrangement of the months and days.

Similar letters of reference indicate corresponding parts in the several figures.

The object of this invention is to produce a simple and cheap calendar which may be readily applied to a pencil-case, match-box, to the head of a cane, watch-seal, key, or other similar articles, and made highly ornamental and convenient for finding the days of the month.

My invention consists in combining together a number of sliding rings having the year and names of the months and names of the days of the week suitably printed or stamped on them, with a column of numerals which will, when suitably arranged on a stem in a proper relation to the rings aforesaid, indicate the days of the month, all as will be hereinafter fully explained.

To enable those skilled in the art to fully understand my invention, I will proceed to describe its construction and operation.

A represents a stem which receives the combination of rings hereinafter to be described. This stem may be made round or septilateral, and it may be made of any desirable size. The stem A may form the head of a walking-cane, pocket inkstand or match-safe, watch-seal, key, or any like article. On this stem, which in the drawings is septilateral, a number of rings are slipped, which should fit tightly on the stem. The (first) ring b has the names of two of the months—January and February—suitably engraved or printed on its surfaces, as shown in Fig. 4 of the drawings. The ring c has the names of seven months engraved on it, arranged as shown in Fig. 4 of the drawings, and ring d

has the names of three months engraved on it—viz., July, December, and November—also shown in Fig. 4. These three rings, b, c, and d, contain the names of the twelve months. The next ring, e, has the names of the days of the week engraved on its surfaces, and this ring is put on the stem A in the order shown in Fig. 1.

A cap, B, having a column of figures from 1 to 31, is now put over the end of the stem A and completes the calendar. The figures on cap B run spirally round the cap B from one end to the other, Fig. 1, commencing on the end next to the ring e, as shown in Figs. 1 and 4 of the drawings. The cap B is confined in its place on stem A by a spring, g, (shown in Fig. 2,) which presses outward against the inside surface of cap B and prevents this cap from casually slipping off. The calendar is now adjusted in the following manner: The slide-sections b c d, which are the twelve lunar months, are slipped on the stem A so that February, March, and November will come in the same space, except for leap-year. Then January, April, and July must be in the same space. These sections b c d may remain in one position, except the above-described adjustment for leap-year. The section or ring e, on which are marked the days of the week, is adjusted each year on 1st of January by placing the proper day in the same space with the word "January" on ring b. This section e remains thus for one year, and indicates for this length of time the day of the week on which each month begins. Find the month, and opposite in the same space will be the day on which it occurs.

The section or cap B, on which are engraved the days of the month, arranged in a spiral column, is adjusted on the first day of each month by placing the space containing the figures 1 8 15 22 29 opposite the proper month. When these adjustments are made, as described, the day of the week and month are readily found in the same space. The day of the week on which any month begins is readily found opposite the month in the same space. If January stands opposite April and July, it is leap-year; otherwise not. To find the number of days in any month, look

for the next succeeding month. If it stands in the same space, the month has twenty-eight days, and add one day for every space the succeeding month is removed from it.

This calendar is more easily read than dial-calendars, as the eye is not confused by a profusion of letters and figures, as only those which occur in one space are seen at one time.

Having thus described my invention, I do not claim, broadly, the application of a weekly calendar to a pencil-case or like article; but

What I do claim as new, and desire to secure by Letters Patent, is—

The combination of the several removable rings *b c d e* with the column of figures B, arranged on a stem, A, substantially as and for the purposes herein set forth.

J. N. DUDLEY.
